(57) **CLAIM**

The ornamental design for a compact disc player, as shown and described.

DESCRIPTION

FIG. 1 is a top view of a compact disc player of the present invention showing my new design;

FIG. 2 is a side view of the compact disc player of FIG. 1; and,

FIG. 3 is a bottom view of the compact disc player of FIG. 1.

Broken lines used in FIGS. 1, 2 and 3 show the environment in which the present invention may be used, but do not form a part of the claimed design.
